Primary Examiner — Lucy Lieberman(74) *Attorney, Agent, or Firm* — Collen IP; Donald J. Ranft(57) **CLAIM**

The ornamental design for a watch, as shown and described.

DESCRIPTION

FIG. 1 is a front view of my new, original and ornamental design for a watch;

FIG. 2 is a bottom view thereof;

FIG. 3 is a top view thereof;

FIG. 4 is a right side view thereof;

FIG. 5 is a left side view thereof; and,

FIG. 6 is a front perspective view thereof.

The portions of the watch shown in broken lines form no part of the claimed design.
